UNITED STATES PATENT OFFICE.

FRANK E. STEFFY, OF GREAT FALLS, MONTANA.

HYDRAULIC SIZING-SCREEN.

1,070,552.

Specification of Letters Patent. Patented Aug. 19, 1913.

Application filed October 2, 1912. Serial No. 723,558.

To all whom it may concern:

Be it known that I, FRANK E. STEFFY, citizen of the United States, residing at Great Falls, in the county of Cascade and State of Montana, have invented certain new and useful Improvements in Hydraulic Sizing-Screens, of which the following is a full, clear, and exact description, reference being had to the accompanying drawings, forming a part hereof.

My invention has relation to improvements in hydraulic sizing screens; and it consists in the novel details of construction more fully set forth in the specification and pointed out in the claims.

In the drawings, Figure 1 is a middle vertical longitudinal section of the apparatus, with parts in elevation; Fig. 2 is a vertical transverse section on the line 2—2 of Fig. 1, parts being broken away; Fig. 3 is a horizontal section on the zig-zag line 3—3 of Fig. 1, parts being broken; Fig. 4 is a horizontal sectional detail on the line 4—4 of Fig. 2; Fig. 5 is a middle vertical transverse cross-section through the eccentric and the upper cross-head supported thereby on the line 5—5 of Fig. 2, showing the normal vertical position of the hanger-rod suspended from said cross-head, the drive-shaft being in side elevation; Fig. 6 is a similar section showing the eccentric partly turned, and the cross-head and slide thereof, and the hanger-rod, partially tilted from their normal position in response to the horizontal movements imparted to the screen-tray to which the lower end of the hanger-rod is coupled; Fig. 7 is an enlarged plan or face view of the quadrant and sliding shoe forming the support for the swivel which carries the upper end of the link or end-motion arm, parts being broken; Fig. 8 is a cross-section on the line 8—8 of Fig. 7 with the link arm and controlling spring therefor shown dotted; Fig. 9 is a diagrammatic view illustrating the motions imparted to the screen, end-motion arms, and hanger-rods; Fig. 10 is a top plan of a modified form of bearing for the fulerum end of the end-motion arm; and Fig. 11 is an end elevation thereof.

As well understood in the art, screening constitutes one of the elements of ore dressing, the crushed ore coming from the finishing rolls passing over a screen the mesh of which constitutes the standard of crushing of the mill. The material which passes

through the mesh is then sized and classified by screens and hydraulic separators. The prevailing sizing screen does not work as efficiently as desirable, and is open to the objection in that it does not segregate from the coarser particles, the exceedingly fine grains and matter known as slime (when mixed with water) a portion of which is carried off with the oversize or material too coarse to pass through the mesh of the screen. In any operation of sizing by means of screens, inefficiency results from increased cost of screening, a large number of screens being required, and the material necessitating frequent rehandling. Not only does such a method impose excessive wear on the screens and other machinery, but much valuable mineral is lost in the form of slime or fines, being carried away by the oversize, it being well known that concentrating machines designed to treat the oversize have not the inherent capacity to save the values contained in the fines associated therewith, not being designed to treat such very fine material.

It is therefore the object of my invention to increase to a maximum the efficiency of screen-sizing, this being accomplished by associating with the screening action a hydraulic separation which not only completely separates the individual particles from one another, but washes free the adhering particles of slime or fines which, in conjunction with the movements imparted to the screen, assist in keeping the screen apertures open. The oversize thus becomes thoroughly deslimed, permitting of independent concentration of the slimes and hence the recovery of the bulk of the values identified with this fine material. In my invention the deslimed oversize is also completely dewatered as it leaves the screen, being thus brought to a condition favorable to the specific mode of treatment or concentration adopted for relatively coarser material.

The advantages of the present invention will be apparent from a detailed description thereof, which is as follows:

Referring to the drawings, and for the present to Figs. 1 to 8 inclusive, 1 represents a tank made preferably of wood, the same being divided into a series of compartments or hatches *a*, *b*, *c*, (three here being shown) by partitions *w*, *w'*. Positioned within the tank is the screen tray 2 pro-

vided with a forward downwardly inclined extension 2' which projects through and beyond the front terminal wall w' of the tank, said wall being made of two sections 5 disposed one on either side of said extension (Fig. 1). The tank 1 is reinforced by buckstays 3 connected at the top by cap-pieces 4 which support the shafting. No novelty however, is attached to such features as they 10 are well understood in the art. The tray 2 carries the horizontal screen 5 deposited on a wooden frame of transversely disposed ribs r forming the bottom of the tray, the sides of the screen being clamped to the 15 frame by means of stringers 6 forced against the screen by means of wedges 7 driven between them and the lugs or plates 8 secured to the sides of the tray 2. The extension is provided with an inclined screen 5' secured 20 in position in any mechanical manner, a bottom guard or apron 9 being secured to the front of the extension to direct the water into the compartment c . The several compartments are provided with discharge 25 plugs 10 having an inwardly flaring passage h (Fig. 1). The forward terminal of the screen-tray 2 proper is connected to the wall w' by means of a flexible diaphragm or hinge 11 of leather, rubber or equivalent 30 flexible sheet material, said diaphragm preventing intercommunication between the compartments b and c . The diaphragm is convexed toward the compartment b and permits of a combined vertical and horizontal 35 reciprocation being imparted to the tray 2 and the screens 5, 5', as will be more fully hereinafter described. Mounted over the rear end of the tank 1 is the feed-box B (preferably lined with iron i) from which 40 lead a series of transversely disposed cast iron spouts 12 discharging the pulp directly over the rubber lining 13 with which the rear end of the tray 2 is provided. Below the plugs 10 are arranged launders or boxes 45 L in which the material discharged from the respective compartments a , b , c , is caught.

Under the present invention, a reciprocating movement must be imparted to the screen both vertically, and at the same time 50 horizontally, the resultant of these motions not only serving to cause the fines to pass through the meshes of the screen into their respective compartments, but to progressively advance the oversize along the screen 55 5 toward the dewatering extension 2', and over its screen 5'. The vertical reciprocation is accomplished by the following mechanism:—Pivotal secured to suitable straps 14 at the sides of the screen-tray are the 60 lower ends of the (two pairs of) hanger rods 15 whose upper screw-threaded portions are passed through the ends of the pairs of cross-heads 16, 16', suitable jam-nuts n being provided where convenient to 65 allow for proper fastening and adjustment

of the parts (Fig. 2). The lower ends of the hanger rods have steel-bushed eyes (in turn supplied with a brass bushing), each pair of rods (on opposite sides of the tray) having a common transverse bolt 17 passed through the eyes and the strap-ends between which the eyes of the rods are received. As previously stated, the cap-pieces 4 support the shafting, each cap-piece being provided with a bearing 18 for the support of the drive-shaft S operated by the belt-pulley P (or equivalent manner). The shaft is provided with any conventional form of adjustable eccentric, 19 the strap or ring 20 of which operates between the cross-heads 16, 16', a slide 21 adapted to longitudinally traverse the cross-head 16 being interposed between the eccentric strap 20 and said cross-head. It is quite apparent from the parts just described, that when rotation is imparted to the shaft S, the eccentric will impart a vertically reciprocating motion to the cross-heads and hence to the hanger-rods and to the screen-tray suspended therefrom, the slide 21 (which has a tongue and groove connection with the cross-head 16) reciprocating back and forth along the cross-head 16 to conform to the horizontal travel of the strap 20 as it is being driven by the eccentric. The eccentric being adjustable, it follows that the degree of eccentricity may be varied by the operator whereby a greater or less vertical throw may be imparted to the cross-heads and hence to the screen-tray. Any standard make of adjustable eccentric 100 may be employed as already stated.

It will be seen from the drawings that the contacting or engaging surfaces between the strap 20 and slide 21 are respectively convex and concave following the surface of a 105 sphere whose center lies on the axis of the shaft S. This curved surface of contact between the parts mentioned results in a sort of ball and socket joint, thus permitting the slide 21 to play over the surface of the strap or ring 20 in a plane at right angles to the plane of rotation of the eccentric (Fig. 6), and hence permitting the hanger-rods and the cross-heads to which they are coupled, to 110 oscillate about the center of the joint aforesaid, which center as previously stated lies on the axis of the shaft S. The oscillation just referred to will obviously be in a plane parallel to the axis of the shaft, and since the screen-tray is suspended from the 115 hanger-rods to which this oscillation may be imparted, it follows that the tray may reciprocate not only vertically but at the same time horizontally, said horizontal movement being necessarily longitudinal with the tray 120 because parallel to the shaft S. The mechanism by which this horizontal movement is imparted to the screen-tray while the latter is reciprocating vertically may vary, the following being an example:—Bolted to the 125

inner faces of the rear extensions 1' of the side walls of the tank 1 are cast-iron quadrants 22 each provided with an arcuate slot or way s , the curvature following the arc of a circle. Along this slot is freely adjustable a cast-iron base or shoe 23 shown in detail in Fig. 8, to which a cap-plate 24 may be secured, the heads of the bolts t by which the parts are secured spanning the sides of the slot. The shoe and cap-plate are suitably cored to receive the trunnions m , m , of a cored swivel 25, the swivel rotating in a plane parallel to the face of the quadrant. Through the opening D of the swivel freely 15 passes a forwardly and downwardly inclined link or end-motion arm 26, whose lower end is pivotally secured between the ears e of the castings 27 bolted on opposite faces of the sides of the screen-tray, the link being provided with jam-nuts n' , n'' , for changing the effective length thereof, a coiled compression spring 28 being interposed between the swivel 25 and the nuts n' for purposes not only of cushioning the jar of the shake of 20 the screen, but for maintaining a substantially fixed length for the link once the same has been adjusted by the proper shifting of the jam-nuts n' , n'' . It will be seen that by shifting the shoe 23 along the quadrant and 25 adjusting the effective length of the link or end-motion arm 26, any variety of horizontal strokes for the screen may be effected; and since the vertical strokes may likewise be adjusted by a proper adjustment of the eccentric, the character and degree of reciprocation to be imparted to the screen may be varied at pleasure depending on the nature and size of material to be sized or treated.

40 As the screen-tray reciprocates vertically under the action of the eccentrics 19, it is apparent that the links 26 coupled as they are to the tray, will be oscillated in a vertical plane; but since the links oscillate along 45 arcs of circles whose centers are substantially on the axes of the swivels 25, the screen-tray will be reciprocated horizontally through a distance represented by the horizontal component of the chord of the arc described by the lower end of each link, the vertical component being necessarily responsive to the vertical throw resulting from the action of the eccentrics. It follows that by virtue of the links or end-motion arms 50 55 26, the motion of the screen is resolved into an upward and forward stroke with a rising movement of the screen, thereby throwing the feed or pulp forward and causing it to travel rapidly over the screen toward the dewatering extension 2'. With a falling of the screen the motion is downward and rearward thereby giving the particles suspended in the water in the tank 1 opportunity to fall onto fresh portions of the screen when 60 65 they are pushed forward with the next or

subsequent upward stroke. In these horizontal reciprocations of the screen-tray, it is obvious that the hanger-rods 15 will oscillate about a point on the axis of the shaft S as a center, the concave surfaces of the slides 21 readily playing over the convex surfaces of the straps 20 (Fig. 6). If desirable the hanger-rods 15 and the cross-heads 16, 16', may be steadied by means of guide-bars 29 connecting the adjacent ends of the cross-heads and operating loosely (in one direction) in hollow bearings 30 of suitable castings 31 bolted to a longitudinal timber or stringer 32 spanning the cap-pieces 4.

The pulp flows from the feed-box through the spouts 12 onto the rubber distributor lining 13 whence it flows in sheet form over the screen 5, the screen being just submerged or close to the surface of the water in the tank 1 when it reaches the limit of its upward and forward stroke. In Fig. 9 I have shown diagrammatically and to the best advantage the operation of the screen. As the eccentrics 19 reciprocate the hanger-rods 15 vertically, the link-arms 26 will cause the screw-tray 2 and screen 5 (and the parts 2', 5') to oscillate horizontally, the resultant following substantially the chord v of the arc y described by the lower-end of the arm 26. The chord v forms the hypotenuse of a right angled triangle the perpendicular p of which represents the effective vertical double stroke or throw to which the screen is subjected, the base k representing the horizontal component or the total distance traversed by the screen horizontally for a given inclination of the link-arm 26. By shifting the center of oscillation of the link-arm, a mere matter of adjustment of the shoe 23 along the slot s of the casting 22 and by varying the effective length of the link-arm, and by varying the effective eccentricity of the eccentric, it is clear that any desired shake or reciprocation may be imparted to the screen. By reducing the throw of the eccentric 19, the vertical component of the inclined path imparted to the screen will be reduced; by lengthening the arms 26 the greater will be the horizontal component of the path described by the screen; by lowering the centers of oscillation of the link-arms the less will be the horizontal displacement of the screen; by raising the centers of oscillation of the link-arms the greater will be the horizontal component of the inclined path or reciprocation of the screen. These are matters quite obvious from the diagrammatic illustration in Fig. 9 in which the link-arm is shown substantially at forty-five degrees to the horizontal when at the center of its arc of oscillation. A shifting of its center of oscillation or a change in its effective length will at once obviously affect the direction of the arc described by the lower end thereof, or that

coupled to the screen-tray and hence vary the horizontal throw of the screen for any given vertical reciprocation of the latter. The vertical reciprocation or component on the other hand may be changed by proper adjustment of the eccentric 19. Referring again to Fig. 9, a particle of ore resting on the screen at the point o when the screen is down, will be elevated to the point o' as the screen is raised. When next the screen is depressed said particle will be left behind (because suspended in the water in the tank) and precipitate onto the screen to the point o'' ; when the screen is next elevated the particle is raised to the point o^3 and with the next depression of the screen the particle drops to the point o^4 (and so on). Since the particle will always fall substantially vertically whereas the screen falls and rises diagonally, it follows that the particle will be progressively advanced forward along the screen 5 until it reaches the inclined screen 5' where it is dewatered, the water flowing through the screen 5' into the empty compartment c , and the particle discharging over the edge of the extension-screen 5' and caught in a suitable receptacle (not shown). The path of the particle as just described is the common path described by all particles which are too large to pass through the screen (5), such particles collectively constituting the oversize. In the reciprocations of the screen the undersize or fine particles or slime become detached from the oversize by the water in the tank (in which the screen is practically at all times submerged) and work their way through the meshes or apertures of the screen, finally settling through the water to the bottom of the compartments a, b , whence they are discharged as a stream of slime through the plugs 10. The presence of the water in the tank 1, and the specific character of reciprocation or shake imparted to the screen while submerged has the effect of not only advancing forward the oversize along the screen, but in desliming the oversize, the fines all passing through the meshes of the screen beneath the screen and settling to the bottom of their respective compartments. The deslimed oversize finally is worked off the extension screen 5' where it is dewatered, the water drained therefrom being caught in the empty compartment c as already described. The oversize thus deslimed and dewatered may be readily concentrated because no longer interfered with by adhering slime particles; and the slimes on the other hand may be separately treated without loss in values. This is a decided advantage flowing from the use of my invention. In Fig. 1 the water level in the tank 1 is represented by the dotted line α being a shade above the plane reached by the screen when at its highest elevation.

As stated above, the swivel 25 constitutes but one form of pivotal connection for the fixed or fulcrum end of the link-arm 26; and in Figs. 10 and 11 I show a modified form of shoe 23' provided with lobes E for the passage of suitable securing bolts (such as t) by which the shoe may be adjusted along the slot s of the quadrant 22. The shoe 23' is provided with a passage-way D' having inwardly convex walls, that is to say, cylindrical walls gradually flaring outwardly in both directions whereby the link 26 with its upper end supported in said passage-way D' is free to oscillate the necessary distance while performing its function as an end-motion arm (see dotted positions in Figs. 10, 11). Any other equivalent form of link connection may be substituted.

Should the water accompanying the pulp from the box B be insufficient to maintain the contents of the tank 1 at the proper level (α), additional water may be introduced through pipes W entering the side of the tank. In the final dewatering of the oversize on the screen 5', not only water, but some slime and other material will pass through this screen into the empty compartment c ; and if the slimes have sufficient value they may be saved and subsequently suitably treated; otherwise the contents of the compartment c are discarded.

Having described my invention, what I claim is:

1. In combination with a water-tank, a screen disposed adjacent the surface of the water in the tank, means for conducting a pulp sheet over the screen, means for imparting combined horizontal and vertical reciprocations to the screen beneath the surface of the water in the tank, and a dewatering extension carried by the screen and inclined downwardly and outwardly from the main body of the screen for the discharge of the oversize.

2. In combination with a tank containing a desliming body of water, a screen positioned adjacent the surface of said water-body, means for feeding a pulp sheet over the screen, means for alternately depressing and raising the screen in the water-body and imparting a horizontal reciprocation thereto, a downwardly and outwardly inclined screen-extension carried by the screen and projecting beyond and out of the desliming water-body, and a container for catching the water and slime passed through the extension, the latter having an edge over which the oversize may discharge to a point beyond the container.

3. In combination with a water-tank, a screen positioned adjacent to the surface of the water in the tank, means for discharging pulp in sheet form onto the screen, means for imparting proper reciprocations to the screen beneath the surface of the

water in the tank for advancing the oversize of the pulp in a given direction along the screen, a water-tight flexible member connecting the screen to the tank, and a perforated member forming an extension of the screen for dewatering the oversize at a point beyond the flexible connection.

4. In combination with a water-tank, a screen positioned adjacent to the surface of the water in the tank, means for delivering pulp onto the screen, means for imparting simultaneous vertical and horizontal reciprocations to the screen beneath the surface of the water in the tank, whereby the solid material of the pulp is advanced along the screen in a given direction, a water-tight flexible member connecting the screen to the tank, an empty compartment beyond the flexible member, a screen extension overhanging said empty compartment and receiving the oversize advanced along the sub-

merged portion of the screen and discharging said oversize at a point beyond said empty compartment, the latter catching the water drained from the oversize accumulating on the screen extension. 25

5. In combination with a tank filled with water, a shaking screen submergible beneath the surface of the water, a water-tight flexible connection between the screen and a wall of the tank, an empty compartment adjacent the wall to which the flexible connection is secured, and a screen dewatering extension above the flexible connection projecting over the empty compartment. 30 35

In testimony whereof I affix my signature, in presence of two witnesses.

FRANK E. STEFFY.
